UNITED STATES PATENT OFFICE.

LAEONCE FRANCIS HYMEL, OF NEW ORLEANS, LOUISIANA.

PERMUTATION SWITCH.

Application filed October 16, 1922. Serial No. 594,946.

To all whom it may concern:

Be it known that I, LAEONCE F. HYMEL, a citizen of the United States, residing at New Orleans, in the parish of Orleans and State of Louisiana, have invented certain new and useful Improvements in Permutation Switches; and I do declare the following to be a full, clear, and exact description of the invention, such as will enable others skilled in the art to which it appertains to make and use the same.

My invention relates to improvements in switches and permutation locks therefor, designed primarily for use upon the ignition circuits or other circuits necessary to operate automobile motors and other internal combustion engines.

One object of the invention is to provide an improved and simplified switch mechanism which may be made to either control only the ignition circuit or to control this circuit and at the same time act as means for grounding the generator or magneto of the motor, it being of course understood that when the ignition switch is open, the grounding switch is closed, and vice versa.

A further object of the invention is to provide improved permutation locking and operating means for the switch including tumblers which may be adjusted to vary the combination of the lock and brake rings between the tumblers fixed with respect thereto, whereby friction cannot be transmitted from one tumbler to the next to turn the latter when it is not desired.

Another object is to provide a locking mechanism in which a single rotatable shaft serves first to aline the tumblers and then acts further to positively move the switch member or members.

With the foregoing in view, the invention resides in the novel subject matter herein-after described and claimed, the description being supplemented by the accompanying drawings.

Figures 1, 2 and 3 are elevations with the cover plate of the casing removed, showing different positions of the parts.

Figures 4 and 5 are horizontal sectional views as indicated by lines 4-4 and 5-5 of Fig. 3.

Figure 6 is a vertical longitudinal section as indicated by line 6-6 of Fig. 4.

Figures 7 and 8 are transverse sectional views as indicated by lines 7-7 and 8-8 of Fig. 3.

Figures 9 and 10 are detail vertical sections on lines 9-9 and 10-10 of Fig. 7.

Figure 11 is a side elevation of one of the brake rings employed between the tumblers.

Figure 12 is an elevation of one of the collars forming part of the pick-up connections between the tumblers.

Figure 13 is an elevation of the retainer which holds the tumblers and associated parts upon their carrying shafts.

In the drawings above briefly described, the numeral 1 designates an appropriate casing adapted to be suitably mounted on an instrument board 2 or on any other desired support. When the device is used on an automobile, the casing 1 is at the front side of the instrument board and only the operating knob 3 for the switch mechanism and the graduated dials 4, are exposed, so that it is practically impossible to gain access to the interior of the casing to complete the ignition circuit of the machine by unauthorized means. In securing the casing 1 to the instrument board 2, I preferably employ bolts 5 having their nuts 6 received non-rotatably in pockets 7 formed in one side of the casing and if desired these nuts may be locked so that it is an impossibility to remove the casing from the instrument board, without unlocking the nuts.

Mounted within the casing 1 is an elongated track-like contact 8 which is secured in the present showing, to an insulating block 9, the latter being in turn secured to one wall of the casing 1. One wire 10 of the ignition or any other desired circuit is electrically connected with the contact 8 by any suitable means such as the clamp 11. Another wire 12 of the circuit extends through the side of the casing opposite the wire 10 and is provided on its inner end with a cap 13 (see Fig. 8) to which one end of a flexible electric conductor 14 is secured. The other end of this conductor is electrically connected with a metal head 15 having a contact spring 16 for engagement with the fixed contact 8 to complete the circuit. One or both of the wires 10-12 is suitably armored to prevent cutting thereof and consequent shunting of the circuit around the switch by unauthorized persons.

In the present showing, the metallic head 15 is provided with an integral neck 17 secured to an insulating block 18 which is in turn secured to an elongated metal switch

controlling member 19 having both lateral and longitudinal movement. In the present form of my invention, the switch member 19 is pivoted at 20 to an arm 21, the latter being preferably weighted so that it will remain in the position shown in Fig. 1 when the arm 19 is in a position to disengage the contacts 8 and 16. When in the position in question, the weighted arm 19 preferably rests upon a contact 23 suitably carried by and insulated from one side of the casing, said contact being in electrical engagement with a wire 24 of the generator or magneto circuit. Thus, when the ignition switch is opened, the circuit of the generator or magneto is grounded to still further interfere with operation of the motor.

By proper movement of the permutation locking means yet to be described, the arm 19 may be moved laterally so that its contact 16 rests upon the fixed contact 8 and said arm may then be moved longitudinally to the position shown in Fig. 2. During this movement, the contact 16 slides upon the contact 8 and the free end of the arm 19 engages with a spring detent or the like 25 which is fixedly mounted within the casing, the arm being provided with a shallow seat 26 into which the detent 25 snaps. It will thus be seen that the detent or shoe 25 holds the arm 19 in such a manner as to effectively retain the contacts 16 and 8 in engagement with each other, at the same time holding the arm 21 off of the contact 23 so that the generator or the like may operate (see Fig. 2).

While the swinging arm 21 may be mounted in any desired manner, I prefer to pivot the same upon a rigid stub 27 which extends from one side of the casing 1. I also prefer to provide this casing with at least one internal stop 27' to limit the movement of the arm 21 in one direction as seen in Fig. 2, and if desired another stop may be employed to restrict the movement of said arm in the opposite direction.

The free end of the arm 19, in the preferred form of construction, is provided with a laterally extending lug 28 having a notch 29, whereby said arm may interengage with the notched outer end 30 of a lateral plate 31 which is mounted on the inner end of the operating shaft 32 which is secured to the knob 3. Plate 31 is preferably threaded and keyed upon the shaft 32 as indicated at 33 in Figs. 5 and 7 and in the present showing, the plate in question is provided with an inwardly extending hub 34 rotatably received in a stub shaft 35 integral with one side of the casing and parallel with the stub 22, serving as bearing means for the shaft 32. Rotatable upon the stub shaft 35 are the tumblers 36 of the locking mechanism, said tumblers having notches 37 which are adapted to be alined as

seen for instance in Figs. 2, 3, 4 and 7, whereby to receive an arm 38 which extends rigidly from the arm 19. Thus, whereas this arm 38 normally rests upon the edges of the tumblers 36 as seen in Fig. 1, the moment the notches 37 are alined, the arm 38 may move into said notches, thereby permitting the contact 16 to engage the contact 8. A spring 39 is preferably employed to shift the arm 19 so that its lateral arm 38 will engage the notches 37 and when the parts stand in the position shown in Fig. 1, this spring is of course under tension in readiness to act. As soon as the arm shifts under the action of this spring, the arm 19 operatively engages the plate 31 as seen in Fig. 3, whereupon turning of the knob 3 in the proper direction will cause said plate to move arm 19 longitudinally into engagement with the shoe or detent 25 as seen in Fig. 2 thus holding the contacts 16 and 8 in proper engagement with each other and retaining the arm 21 away from the contact 23. The machine is now in condition for operation, but it will be seen that as there is no means provided except the knob 3 for alining the notches 37 of the tumblers 36, only authorized persons can place the switch in condition for operation.

In the present showing, each of the tumblers 36 is provided on one side with an arcuate spacing flange 40 whose ends co-act with a radial lug 41 on a collar 42 which is free to rotate on the stub 35, one of these collars being positioned within each flange 40 as will be clear by reference to Figs. 7 and 9. The side of each tumbler 36 opposite the flange 40, with one exception, is provided with a laterally extending projection 43 and this projection of each tumbler extends into the space within the flange 40 of the next adjacent tumbler for co-action with the lug 41 of the adjacent collar 42 (see Figs. 7 and 9). The lug 41 on one of the endmost tumblers 42, is in the path of a projecting pin or the like 44 carried by plate 31 as shown for instance in Figs. 7 and 10. It will thus be seen that turning of the plate 31 through the instrumentality of the knob 3 and shaft 32, will cause the pin 44 to rotate the adjacent collar 42, thereby causing the lug 41 of this collar to co-act with the flange 40 of the next adjacent tumbler 36 to turn this tumbler. The tumbler in question in turn operates the next adjacent collar 42 and the latter turns the next tumbler. Thus, by turning the shaft in a predetermined manner all of the tumblers may be positioned so that their notches 37 aline, permitting closing of the switch 16-8 and opening of the switch 21-23 (see Fig. 2).

To prevent the transfer of movement from one tumbler to the next by friction, after proper setting, I provide a plurality of very thin brake rings 45 which are suitably interposed between the several tumblers, said

brake rings being fixed upon the stub shaft 35, for instance by providing them with lugs 46 received in grooves 47 in said stub shaft. The several tumblers and the collars 5 42 are held in proper relation with the brake rings 45 by means of a U-shaped retainer 48 (see Fig. 13) which straddles the free end of the stub shaft 35 and is received in a peripheral groove 49 thereof.

10 Each of the tumblers 36 preferably consists of an outer annular section 50 formed of metal and an inner section 51 which may well be formed of fibre. The peripheral portion of the section 51 is received between 15 an internal shoulder 52 adjacent one side of the section 50 and a plate 53 secured to the other side of said section. Radial set-screws 54 threaded through the outer sections 50 of the tumblers normally engage the 20 inner sections 51 so as to lock the two against relative turning. By loosening these set-screws, however, the inner sections 51 which carry the flanges 40 may be adjusted within the outer sections 50 having the 25 notches 37. It will thus be seen that the combination at which the lock must be set in order to operate the switch may be varied in a great number of different ways.

As excellent results have been obtained 30 from the construction shown herein and described, this construction is preferably followed, but it is to be understood that within the scope of the invention as claimed, numerous minor changes may be made. Furthermore, the use of my invention is not 35 restricted to any particular circuit or circuits but it may be employed wherever desirable.

I claim:

40 1. A permutation switch comprising a casing having an internal fixed contact, a longitudinally and laterally movable switch member in said casing, permutation means associated with said switch member for effecting lateral movement thereof into engagement with said fixed contact and for then moving said switch member longitudinally, and relatively stationary means in the casing with which said switch member 45 is engaged by said longitudinal movement to hold said member in engagement with said fixed contact.

50 2. A permutation switch comprising a casing having an internal fixed contact of

track-like form, a switch member in said 55 casing movable longitudinally and laterally, said switch member having a contact normally spaced from said fixed track-like contact, permutation means associated with said switch member for effecting lateral movement 60 thereof to bring its contact into engagement with said fixed track-like contact, said permutation means being then operable to move said switch member longitudinally, and relatively stationary means in the cas- 65 ing with which said switch member is engaged by said longitudinal movement to hold the contact of said switch member in engagement with said track-like fixed contact upon which it slides during said longitudinal movement.

3. A structure as specified in claim 1, said relatively stationary holding means consisting of a yielding shoe, said switch member having a seat into which said shoe 75 snaps.

4. A permutation switch comprising a casing having an internal fixed contact, a longitudinally and laterally movable switch member in said casing, permutation means 80 associated with said switch member for effecting lateral movement thereof into engagement with said fixed contact and for then moving said switch member longitudinally, an independent switch member 85 mounted in the casing and connected to said first named switch member to be operated by the longitudinal movement of the latter, and a second relatively fixed contact in the casing 90 co-operable with said independent switch member.

5. A permutation switch comprising a casing having an internal fixed contact, a longitudinally and laterally movable switch member in said casing, permutation means 95 associated with said switch member for effecting lateral movement thereof into engagement with said fixed contact and for then moving said switch member longitudinally, an independent switch member 100 mounted pivotally in said casing and pivoted to said first named switch member, and a second relatively fixed contact in the casing co-operable with said independent switch member.

In testimony whereof I have hereunto affixed my signature.

LAEONCE FRANCIS HYMEL.
